UNITED STATES PATENT OFFICE.

EDWIN S. ANTISDALE, OF CHICAGO, ILLINOIS.

CUFF-PROTECTOR OR HOOK.

1,039,738.

Specification of Letters Patent. Patented Mar. 10, 1914.

Application filed May 18, 1908. Serial No. 433,360.

To all whom it may concern:

Be it known that I, EDWIN S. ANTISDALE, a citizen of the United States, and a resident of Chicago, county of Cook, and State of Illinois, have invented a certain new and useful Cuff-Protector or Hook, of which the following is a specification.

The invention relates to means for protecting a person's cuffs while he is washing his hands or engaged in work which might soil his cuffs, and seeks to provide a simple and effective hook device, which may be readily secured to the inner face of the coat sleeve to engage the outer edge of the cuff and uphold it within the sleeve, and which is provided with a guard lug to prevent the accidental engagement of the hook with the cuff or any portion of the shirt sleeve.

The invention consists in the features of novelty hereinafter set forth, illustrated in the accompanying drawings and more particularly pointed out in the appended claim.

Figure 1 is a side elevation of the improved device applied in place within the coat sleeve which is shown in section. Fig. 2 is a view similar to Fig. 1 with the device in use for holding the cuff within the coat sleeve. Fig. 3 is a perspective view of the form of device shown in Figs. 1 and 2. Figs. 4 and 5 are perspective views of other forms of the cuff protector or hook.

As shown, the improved cuff protector or hook is adapted to be secured to the inner face of the coat sleeve 1 near the end thereof with the hook portion 2 facing inwardly, so that it may be readily engaged with the outer edge of the cuff 3, as shown in Fig. 2, to uphold the latter within the coat sleeve. To prevent the accidental engagement of the hook with the cuff or shirt sleeve, the shank of the hook is provided in front of the mouth of the hook portion 2 with an outwardly projecting guard lug 4. The height of this projecting guard lug is equal to or a little greater than the width of the mouth of the hook, so that it effectively prevents the accidental engagement of the hook with the cuff or shirt sleeve. The guard lug is, however, arranged on the shank of the hook above or a slight distance away from the mouth of the hook, and the space between the guard lug and mouth of the hook is such that the wearer may readily place the outer edge of the cuff into engagement with the hook or disengage the same therefrom. When the cuff is placed in engagement with the hook

by the wearer it will be effectively upheld within the coat sleeve and will not become soiled when the wearer is washing his hands or the like.

The improved device may be formed in different ways, but is preferably constructed of bendable sheet metal or wire. In the forms shown in Figs. 1, 2 and 3, a strip of sheet metal is shaped to form the hook and shank portions 2 and 5. Intermediate its ends, the shank portion 5 of the hook is bent back on itself and thence outwardly to form the projecting guard lug 4 in front of the mouth of the hook, but spaced apart therefrom, so as to prevent the cuff or shirt sleeve from catching in the hook, but without preventing the wearer from readily inserting the outer edge of the cuff in the hook, or disengaging it therefrom. A fastening pin 6 is pivotally connected to the extreme end of the shank and is arranged to engage a catch 7 on the back of the shank.

The form illustrated in Fig. 4 is formed of wire and the outer branch of the hook portion 2' is flattened and provided with an outturned end 8 to facilitate its engagement with the outer edge of the cuff. The shank 9 at a point beyond the mouth of the hook is first bent laterally and then backwardly beneath itself to form the laterally projecting lugs 10 and 11. From the lug 11 the wire body of the hook is bent upwardly and inwardly to form the guard lug 4' in front of the mouth of the hook. At the guard lug 4' the wire is bent at right angles and extends downwardly at an incline to a point substantially in line with the shank 9. At this point it is provided with a spring coil 12 of one or two turns and with a fastener pin 13. The fastener pin is adapted to be forced over the projection 10 and shank 9 after it has been passed through the cloth body of the coat sleeve to securely hold the device in place. The laterally projecting lugs 10 and 11 will rest upon the inner face of the coat sleeve and will hold the hook portion in position to be readily engaged with the cuff. The form shown in Fig. 5 is also made of a continuous length of wire bent to proper form. The hook 2'' and the shank 14 are formed of a doubled bent portion of the wire, so that each has separate side portions. The end of one of the side portions of the shank is bent laterally to form an eye 15. The other side portion is bent laterally to form an eye 16 and

then upwardly and downwardly at an incline to form the guard lug 4". Its extreme end is provided with an eye 17. By means of the eyes 15, 16 and 17, the device may be 5 readily sewed in place upon the inner face of the sleeve.

It is obvious that changes may be made without departure from the essentials of the invention as defined in the claim. By its 10 use the user, when washing his hands or when momentarily engaged in work which might soil his cuffs, may readily protect them by placing the outer edges thereof into engagement with the hook devices secured 15 to the inner faces of his coat sleeves adjacent their ends. The guard lugs effectively prevent any accidental catching of the hooks with the cuffs or shirt sleeves.

Having described my invention, what I 20 claim as new and desire to secure by Letters Patent, is:—

A cuff protector comprising a hook hav-

ing a shank provided with means for securing the same to the inner surface of the coat sleeve, said shank having a broad surface 25 adapted to engage the inner surface of the coat sleeve to hold the hook substantially at right angles to said surface, said hook having an outwardly inclined bill, and said shank having an outwardly projecting, 30 rigid guard lug arranged in front of and in line with the bill of said hook and extending at a greater height than said bill to prevent the accidental engagement of the hook with the cuff, said guard lug being 35 spaced lengthwise of the hook away from the end of the bill to permit the intentional engagement of the cuff with the hook, substantially as described.

EDWIN S. ANTISDALE.
